UNITED STATES PATENT OFFICE

ERNEST HAMWI, OF ST. LOUIS, MISSOURI

DESIGN FOR AN EDIBLE PASTRY CUP

Application filed September 13, 1929. Serial No. 32,748. Term of patent 14 years.

To all whom it may concern:

Be it known that I, ERNEST HAMWI, a citizen of the United States, residing at the city of St. Louis and State of Missouri, have invented a new, original, and ornamental Design for Edible Pastry Cup, substantially as shown in the accompanying drawing, in which—

Fig. 1 is a perspective view looking into the upper end of an edible pastry cup showing my new design.

Fig. 2 is a perspective view looking at the bottom of the pastry cup.

I claim:

The ornamental design for an edible pastry cup, substantially as shown.

ERNEST HAMWI.
